DRAFTSMAN'S INK DISPENSER

Fred I. Goodenow, Kansas City, Mo., and Julian Frank Goodenow, Jr., Johnson County, Kans.

Application September 5, 1947, Serial No. 772,370

1. Claim. (Cl. 120—57)

1

This invention relates to ink dispensers and more particularly to an ink bottle and stopper for discharging small quantities of ink into draftsmen's pens and other inking instruments.

It is customary for drawing ink to be placed in small bottles having a stopper provided with a quill or the like which is utilized for filling of draftsmen's instruments. With such ink bottles and stoppers, it is necessary to remove the stopper from the bottle each time ink is placed in an instrument. Opening and closing of the bottles requires two hands. Furthermore, an open bottle always constitutes a hazard as often the bottles are overturned, spilling ink on the drawing board and drawing, resulting in a damaged or ruined drawing and loss of all of the time required for making or correcting same. Frequently, draftsmen leave the stopper loose to facilitate removal hereof for filling of instruments. This also constitutes a hazard as the stoppers will frequently come out of the bottle if it is overturned, thereby spilling ink on the drawing. Some devices have been used wherein the bottle is placed in a support on which is pivoted a lever for lifting the stopper from the bottle and filling of instruments and the like. Such devices will still overturn and, as with any quill type stopper, there is little control of the amount of ink delivered to the pen.

The objects of the present invention are therefore to provide an ink dispenser for delivering small quantities of ink to draftsmen's instruments without lifting the bottle or removing the stopper; to provide an ink dispenser capable of accurately controlling the delivery of ink or removal thereof from draftsmen's instruments; to provide a substantially non-spillable ink dispenser; to provide for preventing congealing of the ink in the delivery passage while the dispenser is not in use; and to provide a simple, efficient and inexpensive ink dispenser for facilitating the filling of draftsmen's inking instruments.

In accomplishing these and other objects of the present invention, we have provided improved details of structure, the preferred form of which is illustrated in the accompanying drawings wherein:

Fig. 1 is a perspective view of an ink dispenser embodying the features of the present invention, a hand of a user being shown in position for controlling the dispensing of the ink.

Fig. 2 is a side elevation of the dispenser stopper, portions of the dispensing tube being broken away to illustrate the passage and a member therein for preventing stoppage when the dispenser is not in use.

2

Fig. 3 is a vertical sectional view through the dispenser particularly illustrating the positioning of the dispensing tube and the control aperture in the stopper.

Fig. 4 is a plan view of the dispenser stopper and tube.

Referring more in detail to the drawings:

1 designates an ink dispenser consisting of a bottle 2 of ordinary construction for holding drawing ink 3. The bottle preferably consists of a bottom 4 having upwardly extending walls 5 thereon, terminating in an inwardly converging portion 6 to form a reduced neck 7 having an opening 8 therein. The upper portion of the neck 1 is preferably provided with a flange 9. 10 designates a stopper preferably formed of compressible materials, such as soft rubber or the like. The lower portion 11 of the stopper is of the same geometric cross-section as the opening 8 in the bottle neck and is preferably tapered downwardly to facilitate insertion in the opening 8, the relative size being such that the portion 11 is compressed slightly when fully inserted in the opening 8 to provide a positive seal and closure for the bottle 2. A flange 12 surrounds the stopper, forming a shoulder 13 with the lower portion 11, said shoulder being adapted to contact the upper surface of the flange 9 when the stopper portion 11 is tightly engaged in the opening 8.

Extending upwardly from the flange 12 and integral therewith is a compressible top 14, terminating in a rounded upper end 15. The top 14 is provided with an air chamber 16 therein, terminating short of the rounded end 15 of said top 14 as at 17, the air chamber 16 being of such size that the walls 18 of said top are easily compressible to collapse said air chamber 16, and provide return to normal position on release of pressure due to the resiliency of the material from which the stopper is formed. The chamber 16 has communication with the interior of the bottle 2 through a passage 19 extending downwardly through the lower portion 11 of said stopper, the portion of the passage adjacent the lower end 20 of the stopper preferably being flared outwardly as at 21.

An aperture 22 extends through the flange 12 from the passage 19 to the exterior of the stopper adjacent the point of connection between the flange 12 and the top 14, as at 23. Said aperture preferably is arranged at an angle to the vertical center of the stopper and is of such size as to receive and form sealing engagement with the exterior of a delivery tube 24. The tube 24 is of such length that it extends downwardly from the aperture 22 through the passage 19 and

into the bottle 2 terminating substantially adjacent to the bottom 4 as at 25, the upper end of said tube projecting outwardly from the aperture and terminating in a downwardly curved portion 26 to form a spout for the delivery of ink from the bottle as later described.

To prevent air from entering the ink bottle and effecting the congealing of the ink in the tube 24, we provide a wire 27 preferably of spring material and slightly smaller in diameter than the bore 28 of said tube 24, said wire preferably being slightly longer than the tube 24 and terminating at its outer end in a loop 29 to form a handle for manipulation of said wire in inserting and withdrawing of the wire from the bore of the discharge tube. Said wire is particularly for insertion into the tube to maintain the passage therein open and prevent congealing of ink in the tube during periods of non-use of a dispenser.

In order to provide accurate control in the dispensing of ink from the dispenser tube, an aperture 30 is located in the top 14 preferably in the upper end. Said aperture may be of a suitable shape, however it is preferably in the form of a thin slit whereby in normal positions the edges thereof are in contact to substantially seal the aperture. With this construction of the dispenser, the only openings through which air may enter the stopper or bottle are the passage 28 in the discharge tube which terminates below the level of the ink in the bottle and the aperture 30 in the upper end of the stopper top, which normally excludes substantially all of the air except when the top is compressed. Therefore, there is substantially no oxidation or congealing of the ink in the bottle due to entry of air therein when not in use. The lower portion 11 of the stopper tightly engages and seals the opening 8 in the bottle and engagement of the sides of the aperture 22 with the discharge tube 24 seals said aperture to prevent entry of air around said tube.

In using a device constructed as described, the stopper is removed from the bottle and ink placed therein. The lower portion 11 of the stopper is then inserted into the opening 8 of the bottle and pressed downwardly to seal same, the sides of the lower portion preferably having a groove 31 therein terminating as at 32 in spaced relation to the shoulder 13 whereby air may escape from the bottle as the stopper is pressed therein, substantially eliminating any bubbling of ink from the bottle during insertion of the stopper, there being sufficient space between the groove 31 and the shoulder 13 to provide adequate sealing surface between the lower portion 11 of the stopper and the opening 8 of the bottle. With the wire 27 in the passage 28 of the discharge tube 24 and the edges of the aperture 30 having engagement, the bottle is substantially sealed and may be transported, overturned or otherwise handled without spilling any of the ink from the dispenser. Therefore a draftsman may have the dispenser on his board and does not have to exercise any care to prevent the overturning of the bottle. At the beginning of the day or when the draftsman begins the inking of a drawing, the handle 29 of the wire 27 is grasped to withdraw the wire from the discharge tube 24. The wire may be laid aside for the entire day or during the inking process of the drawing. The draftsman then places the instrument adjacent the outer end of the discharge tube 24 and by placing the forefinger

over the aperture 30 then by pressing the stopper top between the thumb and middle finger, the pressure on the thumb and middle finger will collapse the air chamber 16, forcing the air therefrom through the passage 19 to apply pressure on the upper surface of the ink 3 in the bottle 2. This forces ink through the passage 28 and from the delivery tube into the pen or other instrument being filled. The pressure on the top may be regulated to force the ink out of the delivery tube if desired. If an excess quantity of ink is delivered to the pen or instrument, the ink may be withdrawn from the pen or instrument by pressing the stopper top between the thumb and middle finger and then placing the forefinger over the aperture, then lessening the pressure to force the air from the upper surface of the ink into the air chamber. The lessening of pressure on the stopper top with the end of the delivery tube in the ink in the instrument will effect withdrawal of the ink from the instrument and return same through the delivery tube to the bottle.

Delivery or withdrawal of the ink through the delivery tube may be stopped at any time by lifting the forefinger from covering relation with the aperture 30. With the aperture 30 open, the top 14 may be compressed and released as desired without ink being discharged or withdrawn through the delivery tube. Therefore accurate control of the delivery or withdrawal of ink from the dispenser is maintained by the closing of the aperture 30 and the simultaneous compressing or releasing the stopper top 14.

While the dispenser may be used for many days without replacing the wire 27, it is desirable at the end of the day, or after the inking of a drawing has been completed, to replace the wire 27 in the passage 28 of the tube 24 to maintain the passage free of any stoppage. While the dispenser is being used it may be overturned without danger of spilling ink on the drawings. Therefore the draftsman does not have to exercise any care whatsoever in the protecting of the ink bottle as in ordinary practice.

It is believed obvious that we have invented an ink dispenser which facilitates the filling of draftsmen's inking instruments and completely eliminates any danger of damaging a drawing by the spilling of ink thereon.

What we claim and desire to secure by Letters Patent is:

An ink dispenser comprising, a container having a single opening therein, a stopper formed of resilient material having a portion adapted for insertion into the container opening for sealing same, said stopper having a central passage therein opening to the interior of the container, a compressible top on said stopper and having a central chamber communicating through the stopper passage with the interior of the container for movement of air to and from the container, and a delivery tube extending downwardly through the stopper into the contents of the container and having its outer end projecting outwardly through the stopper, said tube having a through longitudinal passage with openings only at the ends thereof for movement of the contents of the container, said compressible top having a slit remote of the container and positioned to be selectively covered by a finger of an operator when applying pressure to the compressible top, said slit having edges which are normally resiliently engaged to close same, said slit opening only during compression and ex-

expansion of the compressible top to provide communication from the exterior of the stopper to the chamber, passage in the stopper and interior of the container whereby movement of ink out of and into the container through the delivery tube is effected by selective closing of the slit during compression and expansion respectively of the compressible top.
